UNITED STATES PATENT OFFICE.

ABRAHAM C. STEVENSON, OF PHILADELPHIA, PENNSYLVANIA, ASSIGNOR OF ONE-HALF TO ELEANOR ROSS STEVENSON AND ONE-HALF TO DANIEL W. HILDRETH, JR., BOTH OF PHILADELPHIA, PENNSYLVANIA.

HOSPITAL APPLIANCE.

1,157,441.

Specification of Letters Patent.

Patented Oct. 19, 1915.

Application filed October 28, 1914. Serial No. 868,966.

To all whom it may concern:

Be it known that I, ABRAHAM C. STEVENSON, a citizen of the United States of America, residing in the city and county of Philadelphia, in the State of Pennsylvania, have invented certain new and useful Improvements in Hospital Appliances, of which the following is a true and exact description, reference being had to the accompanying 10 drawings, which form a part thereof.

My present invention consists in a bracket or holder especially devised for attachment to a bed to serve as a support for the liquid reservoir employed in giving saline and like 15 injections to a patient resting on the bed.

The general object of my invention is to provide a simple and effective device for the purpose specified, which may be detachably secured to the bed and is well adapted to 20 meet the ordinary conditions of hospital use. For instance, provision must be made for adjusting the height of the reservoir and keeping it plumb when the bed is itself adjusted, for the proper feeding of the injection liquid depends upon the hydrostatic 25 head at the point of discharge. The support for the reservoir must be strong and rigid for each injection period frequently lasts for several hours during which the bed 30 to which the device is attached may be moved or adjusted, and provisions must be made for maintaining the injection liquid at the proper temperature, and the device is subject to other handling and possibility of 35 engagement by the patient or attendants. The device moreover, must be capable of being cleaned easily, and should be so arranged as not to interfere in any way with the cleaning of the floor under the bed while 40 the device is in use.

The various features of novelty which characterize my invention are pointed out with particularity in the claim annexed to and forming a part of this specification. 45 For a better understanding of my invention, however, reference should be had to the accompanying drawings and descriptive matter which I have illustrated and described as a preferred embodiment of my invention.

50 Of the drawings: Figure 1 is an elevation, partly in section, showing my improved holding appliance affixed to the side rail of a metal bed. Fig. 2 is a plan view of a portion of the apparatus shown in Fig. 1. Fig.

3 is an elevation of one, and Fig. 4 is an 55 elevation of the other of a pair of relatively adjustable parts of the apparatus shown in Fig. 1. Fig. 5 is a sectional elevation illustrating a connecting device which may be employed under certain conditions. 60

My improved holding appliance comprises a horizontal member A bifurcated at one end with the two branches A¹ spread apart and adapted to be secured to the horizontal top flange of the usual angle bar side rails Y 65 employed in metallic hospital beds. For this reason each branch or bifurcation A¹ is formed with a downward and backward turned portion A² adapted to catch under the horizontal flange of the bed rail when 70 the member A is mounted thereon. Set screws B threaded through the upper portions of the branches A¹ are employed to detachably secure the member A in place.

At its free end the member A is formed 75 with a cylindrical spindle portion A⁴ and a circumferential flange A³ between the portion A⁴ and the bifurcation A¹. A socket member C is formed with a socket receiving the portion A⁴, and with a flange or collar 80 C¹ adapted to fit against the flange A³. To permit the members A and C to be held together in different angular adjustments about the axis of the part A⁴, the collar A³ is provided with a pin A⁵ which is entered 85 in one or another of a series of sockets C² formed in the flange C¹. The member C is formed with a threaded socket to receive a set screw B⁴ which impinges at its inner end against the extension A⁴ and thereby locks 90 the member C against movement relative to the part A⁴ in a direction parallel to the length of the latter.

At its outer end the member C is formed with an open ended socket C³ receiving a 95 post D which may be secured in different adjustments therein by means of the set screw B². The socket C³ and consequently the post D are ordinarily vertically disposed. At its upper end the member D has a head 100 E attached to it. As shown the head E is formed with four arms E¹ having upturned end portions. In the upturned portions of an adjacent pair of arms E¹ are mounted set screws B³ between which and the upturned portions of the remaining arms the object 105 to be supported may be clamped. As shown this object is the reservoir G for the saline

injection liquid, or rather a metallic cage F in which the reservoir G is mounted. As shown the reservoir G is of glass, formed with a discharge nipple at its lower end to which is attached a hose H for leading the injection liquid to the body of the patient resting on the bed of which the side rail Y forms a part.

The holding device shown is obviously capable of easy attachment to and release from the side rail Y, and the spreading apart of the bifurcations A¹ permits the device to be positively clamped to the side rail at points separated from one another by a considerable distance, thus insuring a very desirable rigidity.

The adjusting provisions disclosed permit the reservoirs held thereby to be adjusted to the proper level and kept plumb, notwithstanding the fact that the position of the side rails are changed from time to time as one end of the bed is raised or lowered relative to the other. The adjusting provisions are of such a simple and positive character moreover, that they can be easily made, and the parts positively secured in their new adjustments by relatively unskilled nurses and attendants.

The appliance is obviously easily cleaned and does not interfere with the movement of the bed over the floor or with the operation of cleaning the portion of the floor under the bed.

With the injection fluid reservoir G positively held in a definite position relative to the bedstead, the hose H may readily be made of such length and so disposed that there is no danger of this hose becoming kinked and the flow of the injection liquid thereby interrupted.

To enable the holding device shown in Figs. 1 to 4 to be supplied to a bed rail of other than the usual angle bar construction, a separate connecting device may be em-

ployed. This connecting device may have a flange corresponding to the horizontal flange of the bed rail shown in Fig. 1 and may be provided with suitable provisions whereby it may be clamped to the side rail; for instance, as shown in Fig. 5, the connecting piece Z may be provided with a split collar adapted to be clamped, as by the bolts Z¹, about a tubular metallic side rail employed in some makes of metallic beds.

Having now described my invention, what I claim as new and desire to secure by Letters Patent, is:

A device for the purpose specified comprising a member bifurcated at one end and terminating at its other end in a spindle portion with a flange surrounding the spindle portion at the inner end of the latter, the branches of said bifurcated end being spaced apart and formed each with a back turned portion adapted to take under the horizontal top flange of a bed angle bar side rail on which the said member may rest, a socket member formed with a socket receiving said spindle portion and with a flange surrounding said socket, and formed also with a second socket transverse to the first, said flanges having parts coöperating to hold said socket member and spindle portion in any angular adjustment in which they may be assembled, means for detachably securing said spindle portion in the first mentioned socket, a post received in said transverse socket and adjustable therein in the direction of its length; means for securing said post in said socket in one or another of its different adjustments, and a liquid reservoir supporting means mounted on the upper end of said post.

ABRAHAM C. STEVENSON.
